UNITED STATES PATENT OFFICE.

FREDERICK GELSTHARP, OF TARENTUM, PENNSYLVANIA, ASSIGNOR TO PITTSBURGH PLATE GLASS COMPANY, A CORPORATION OF PENNSYLVANIA.

APPARATUS FOR MAKING SHEET GLASS.

Application filed May 7, 1923. Serial No. 637,128.

The invention relates to the manufacture of sheet or plate glass, and has for its objects the provision of an improved apparatus for producing glass in a continuous sheet or ribbon from a tank, preferably from a melting tank of the regenerative type. Certain embodiments of the invention are illustrated in the accompanying drawings wherein:

10 Figure 1 is a vertical section through the apparatus. Fig. 2 is a transverse section on the line II—II of Fig. 1. Fig. 3 is a diagrammatic end view of the gearing for driving the rolls. And Fig. 4 is a diagrammatic sectional view illustrating a modification of the structure of Fig. 1 wherein the second pair of rolls are placed at a level below that of the first pair.

Referring to the drawings, 1 is the discharge end or forehearth of a continuous melting tank containing a bath of molten glass 2. The side wall 3 is made in the form of a separate block carried by the metal framework 4 so that it may be readily removed for replacement or repair and is provided with an outlet slot 5 adapted to discharge to the reducing rolls 6 and 7, such rolls being driven as hereinafter described and being hollow and provided with connections 8 and 9 whereby liquid may be supplied to maintain the rolls at any desired temperature. The rolls are carried upon the truck frame 10, and the truck itself is mounted upon the rails 11 which arrangement permits of the movement of the truck laterally when it is desired to repair or replace the rolls and to give access to the slot member 3.

Also mounted upon the truck framework 40 is a second pair of driven water cooled rolls 12 and 13, such rolls being supplied with a cooling medium through connections, not shown, but corresponding to the connections 8 and 9. The truck also carries shade members 14 and 15 supported in a suitable framework of channels and T bars 16 and 17 and a water cooled supporting roll 18 intermediate the two sets of reducing rolls. In some cases it is necessary to employ burners 19 intermediate the two sets of rolls, such burners ordinarily being located adjacent the edges of the sheet which are apt to cool most rapidly, although in some cases it may be desirable to apply heat to the entire width 55 of the sheet.

Intermediate the slot member 3 and the rolls 6 and 7 are located a pair of lips 20 and 21 in the form of angle irons, preferably made of calite, nichrome or other suitable heat resisting metal. These lips may be cooled, or their temperature otherwise regulated by means of air pipes 22 and 23 provided with suitable slots or perforations for directing the air against the lips. The spaces at the ends of the rolls 6 and 7 are preferably closed by triangular metal members 24 which are preferably heated as fully described in my Patent No. 1,560,078 of Nov. 3, 1925.

The shafts of the rollers are provided with tumbler shafts 25, 26, 27 and 28 (Figs. 2 and 3). The shafts 25 and 26 are provided with the intermeshing spur gears 29 and 30, the shaft 26 also being provided with a gear 30^a which is driven from the pinion 31 on the shaft 32. The shaft 32 is driven from the motor 33 through the intermediary of the worm reducing mechanism in the casing 34.

The pinion 31 also drives a spur gear 35 carried by the tumbler shaft 28 (Fig. 3). This shaft 28 carries a spur gear 36 meshing with a similar gear 37 on the tumbler shaft 27. Since the gear 35 is of less diameter than the gear 30, this arrangement provides for driving the rolls 12 and 13 faster than the rolls 6 and 7, this being necessary because the portion of the sheet at 38^a must travel faster than the thicker portion at 38.

Intermediate the two sets of rolls is the supporting roll 18 which is necessary to prevent the sheet from sagging at this point. One or more rolls may be employed depending upon the distance apart of the two sets of reducing rolls, and these rolls may either be idlers or may be driven, but are preferably driven as illustrated, this being accomplished by means of a sprocket 39 which is driven by the sprocket chain 40 passing around a sprocket wheel 41 on the shaft of the roll 7.

In advance of the rolls 12 and 13 is a leer 42, which may be of any desired type, but is preferably provided with rolls 43 having sprockets 44 on their ends driven from the chain 45. The damper 46 is preferably employed at the inlet end of the leer, such damper being supported from cables 46 passing over suitable pulleys and counterweighted.

- While the second pair of reducing rolls 12 and 13 are preferably located on the same level as the first reducing rolls, such rolls may be located at a lower level as indicated at 12^a and 13^a of Fig. 4. Only a single pair of secondary reducing rolls are shown in both the construction of Fig. 1 and Fig. 4, but it will be understood that the invention is not so restricted and that various other modifications might be introduced without departing from the invention which contemplates broadly the use of sizing means to give the sheet its final dimension after passing the first set of rolls which act to control the flow of glass from the tank under the head pressure in such tank. The tendency toward devitrification is reduced where two or more sets of rolls are employed, instead of accomplishing all of the reduction by a single pair of rolls at the outlet of the slot 5, and the placing of the secondary rolls at the same level as the first rolls has the advantage of avoiding the necessity of straightening the sheet again, such as is called for when the sheet is carried to a lower level after passing the rolls 6 and 7 and then turned to the horizontal again on entering the leer. This same advantage is present when all of the reduction of the thickness of the sheet is accomplished by the first pair of rolls 6 and 7, in which case the rear end of the leer 42 can be brought back closer to the rolls 6 and 7. The tendency toward devitrification, referred to above, which exists when a single pair of rolls is used and all the reduction occurs in the one pass, is believed to be due to the existence of a more or less stagnant body of glass of relatively small volume immediately behind the rolls. The glass above and below this volume of glass is positively fed between the rolls because of its contact with the forwardly moving roll surfaces leaving the glass between the two layers thus fed forwardly in a condition of rest and at a temperature (due to the proximity to the rolls) such that devitrification is liable to occur sooner or later, thus introducing into the sheet from time to time small volumes of glass of light color which impair the quality of the glass. With a wider pass between the rolls, there is greater opportunity for the body of glass trapped between the rolls behind the pass to flow forward between the layers of glass pulled forward by the roll surfaces, so that the glass at this point is fed out and replaced by fresh glass in a reduced interval, thus reducing its liability to devitrify.
- 60 What I claim is:
1. In apparatus for making sheet glass continuously in a sheet or ribbon, the combination with a tank or receptacle for molten glass provided with an outlet through its side wall so located as to permit the dis-
  - charge therethrough under the head pressure of the tank, of sheet forming rolls at such outlet with their pass under said head pressure arranged to control the rate of flow of the glass from said outlet and spaced apart a distance greater than the thickness of the finished sheet, and a second pair of rolls in advance of the first pair spaced apart a less distance than such first pair and serving to reduce the thickness of the sheet or ribbon.
  2. In apparatus for making sheet glass continuously in a sheet or ribbon, the combination with a tank or receptacle for molten glass provided with an outlet through its side wall so located as to permit the discharge therethrough under the head pressure of the tank, of sheet forming rolls at such outlet with their pass under said head pressure arranged to control the rate of flow of the glass from said outlet and spaced apart a distance greater than the thickness of the finished sheet, a second pair of rolls in advance of the first pair spaced apart a less distance than such first pair, and a leer in advance of said second pair of rolls.
  3. In apparatus for making sheet glass continuously in a sheet or ribbon, the combination with a tank or receptacle for molten glass provided with an outlet through its side wall so located as to permit the discharge therethrough under the head pressure of the tank, of sheet forming rolls at such outlet with their pass under said head pressure arranged to control the rate of flow of the glass from said outlet and spaced apart a distance greater than the thickness of the finished sheet, and sizing rolls in advance of said rolls for thinning the sheet or ribbon and giving it a uniform and definite thickness.
  4. In apparatus for making sheet glass continuously in a sheet or ribbon, the combination with a tank or receptacle for molten glass provided with an outlet so located as to permit the discharge therethrough under the head pressure of the tank, of sheet forming rolls at such outlet with their pass under said head pressure arranged to control the rate of flow of the glass from said outlet and spaced apart a distance greater than the thickness of the finished sheet, sizing rolls in advance of said rolls for giving the sheet its final thickness, and a leer in advance of said sizing rolls.
  5. In apparatus for making sheet glass continuously in a sheet or ribbon, the combination with a tank or receptacle for molten glass provided with an outlet through its side wall so located as to permit the discharge therethrough under the head pressure of the tank, of sheet forming rolls at such outlet with their pass under said head pressure arranged to control the rate of flow of the glass from said outlet and spaced

apart a distance greater than the thickness of the finished sheet, sizing rolls in advance of said rolls for thinning the sheet or ribbon and giving it a definite and uniform thickness, and a leer in advance of the sizing rolls having a bed for forwarding the sheet or ribbon therethrough, the passes between the rolls and the bed of the leer ly-

ing at substantially the same level so that the sheet is maintained throughout in substantially a single plane. 10

In testimony whereof, I have hereunto subscribed my name this 2nd day of May, 1923.

FREDERICK GELSTHARP.
